RELEASE VALVE LEVER

Charles L. Buhro, Racine, Wis., assignor to Walker Manufacturing Company, a corporation of Delaware
Filed Sept. 19, 1960, Ser. No. 56,792
2 Claims. (Cl. 251—289)

This invention relates generally to jacks and more particularly to a release mechanism for positively controlling the rate of lowering of a hydraulic jack. While it may be used with various jacks it is especially adapted for use with the jack shown in U.S. Patent #2,837,222.

The rate of descent of a conventional hydraulic jack is a function of release valve opening. Ordinarily, the pressure release valve is opened by means of a force applied directly to the release valve actuator, the degree of control over the rate of descent of the jack depending upon the sensitivity of the applied force. However, positive control over the degree of opening the release valve of a hydraulic jack sufficient, for example, to render foot operation practicable, is relatively difficult when the force is applied directly to the release valve. Therefore, in those conditions wherein a safety hazard is present due to inadvertent release of the load supported by the jack, there is a need for a hydraulic jack release mechanism that can be relatively positively controlled.

The present invention is directed to a release mechanism that is operable in two modes, selectively, so as to open the release valve at a controlled rate regardless of the force applied to the release lever, or alternatively, to open the release valve in relation to the force applied. The latter condition is desirable to facilitate lowering of the jack when it is unnecessary to control the rate of descent thereof.

Accordingly, one object of the present invention is an improved mechanism for effecting release of a hydraulic jack.

Another object is a mechanism for positively controlling the rate of descent of a hydraulic jack.

Another object is a release lever operable in different modes to effect lowering of a hydraulic jack at different rates.

Other objects and advantages of the present invention will become apparent from the following specification, claims and drawings wherein a release mechanism, in accordance with an exemplary embodiment of the present invention, is shown in operative association with a conventional hydraulic jack.

A release lever 10 is shown operatively mounted on a hydraulic jack 12 such as the one shown in U.S. Patent #2,837,222. The hydraulic jack 12 comprises a base 14 having suitable legs 16 and 18 for stabilizing the jack against tipping. A manually operated hydraulic pump 20 including a piston 22 and pump handle 24 is supported on the base 14, the pump 20 being connected to a main hydraulic cylinder 26 as by various valves and passages (not shown). The pump handle 24 is pivotally connected to the base 14 by a link 25 in such a manner that pumping of the handle 24 effects concomitant reciprocation of the piston 22 to thereby elevate a ram (not shown) within the main operating cylinder 26.

The jack 12 has an upstanding release valve 30 with an upwardly extending actuator 31 that is operable downwardly to effect release or opening of the valve 30 to release the load sustaining hydraulic pressure in the main hydraulic cylinder 26 and lower the ram (not shown). Ordinarily, the release valve actuator 31 is operable by foot pressure thereon thereby to bias the actuator 31 downwardly with respect to the base 14 of the jack 12. As discussed hereinbefore, the degree of control over the rate of lowering obtained by this expedient is insufficient

2

to accurately control the rate of descent of the ram in those applications where the load is relatively heavy or safety demands more positive control.

In accordance with the present invention, the release lever 10 is of U-shaped configuration defined by a bight portion 40 and leg portions 42 and 44. The release lever 10 is supported for rotation with respect to the base 14 as by a pair of pivotal supports or bolts 46 and 48 that extend through suitable apertures in the end portions 50 and 52 of the legs 42 and 44 and through suitable bosses 54 and 56, respectively, on the base 14.

A stop bracket 60 is secured to the base 14 of the jack 12 as by a pair of bolts 62 and 64. The stop bracket 60 has a horizontally extending stop flange 66 for movement limiting engagement with a lower end portion 68 of a rate adjusting screw 70. The screw 70 is threadably engaged in a nut 72 that is secured to the juncture of the bight portion 40 and leg portion 42 of the lever 10, as by welding. It is to be noted that the nut 72 is displaced to one side of a center line drawn between and normal to the axis of the pivotal supports 46 and 48 of the lever 10. The screw 70 has a head 74 to facilitate rotation thereof with respect to the nut 72 and a locking nut 76 to facilitate locking of the screw 70 against rotation with respect to the nut 72.

A generally L-shaped bracket 80 has a downwardly depending flange 82 secured to the leg 42 of the lever 10 as by welding, and a horizontally extending flange 84 in alignment with the actuator 31 of the release valve 30. Upon downward movement of the lever 10, the flange 84 of the bracket 80 is engageable with the actuator 31 to effect opening of the release valve 30.

Calibration of an index or controlled rate of lowering of the jack 12 is accomplished after installation of the lever 10 on the base 14. The metering screw 70 is advanced downwardly until the flange 84 on the bracket 80 is spaced from the actuator 31 of the release valve 30 when the lower end portion 68 of the screw 70 is engaged with the stop flange 66 on the stop bracket 60.

The operating handle 24 of the jack 12 is then pumped to elevate the ram (not shown), and a load is applied thereto, for example, a load of several hundred pounds when the jack is to be used for lowering transmissions of an automobile. The lever 10 is then biased downwardly by a force applied directly to the head 74 of the screw 70 until the lower end portion 68 of the adjusting screw 70 engages the stop flange 66 of the bracket 60. The adjusting screw 70 is then rotated so as to retract the end portion 68 thereof upwardly, as seen in the drawings, until the flange 84 on the bracket 80 engages the actuator 31 of the release valve 30 and the ram (not shown) begins to descend. When a desired rate of descent is achieved, the lock nut 76 about the screw 70 is tightened thereby establishing the controlled or index rate of lowering.

To lower the jack at the index rate, pressure is applied directly to the head of the rate screw 70 which forces the release lever 10 downwardly until the lower end portion 68 of the screw 70 engages the flange 66 on the stop bracket 60. It is to be noted that engagement of the bottom or end portion 68 of the adjusting screw 70 with the flange 66 positively limits further movement of the lever 10 and therefore opening of the release valve 30, regardless of how "heavy" the foot applied pressure might be. Therefore, in this mode of operation, the preset of the rate adjusting screw 70 controls the rate of descent of the ram (not shown) of the jack.

When it is unnecessary to control the rate of descent of a load supported by the jack 12, the load can be rapidly lowered by stepping on the release lever 10 in the area of the juncture of the bight portion 40 with the leg portion 44. When pressure is applied, as by the foot,

to this portion of the release lever 10, the release lever 10 first pivots downwardly about its pivotal supports 46 and 48 until the lower end portion 68 of the adjustment screw 70 engages the stop flange 66. When this condition obtains, the lever 10 is supported at three points, namely, by the pivotal supports 46 and 48 and the lower end portion 68 of the screw 70. Upon the application of additional pressure to the lever 10 in the area of the juncture of the bight portion 40 and leg 44 thereof, the lever 10 pivots or flexes about a line drawn generally between the pivotal support 48 and the end portion 68 of the adjusting screw 70. As the lever 10 rotates or flexes about this new axis, the leg 42 twists and the flange 84 on the bracket 80 is deflected downwardly, as shown by the dotted line position to bias the actuator 31 of the release valve 30 downwardly. In this manner the natural resilience of the release lever 10 is utilized to permit flexure about the newly obtained axis to effect twisting of the leg portion 42. Twisting of the leg 42 effects downward movement of the flange 84 of the bracket 80 to bias the release valve actuator 31 downwardly beyond the index position reached upon engagement of the screw 70 with the stop 66 thereby opening the release valve 30 to effect lowering of the jack at a rate relatively faster than the index rate.

It is to be understood that the specific construction of the improved jack herein disclosed and described is presented for the purpose of explanation and illustration and is not intended to indicate limits of the invention, the scope of which is defined by the following claims.

What is claimed is:

1. A release mechanism for controlling the rate of lowering of a hydraulic jack having a release valve with an actuator thereon the rate of lowering of said jack being related to movement of the release valve actuator towards the open position, said release mechanism comprising a release lever, means for supporting said lever for rotation about a first axis so as to engage and move the release valve actuator of the jack towards the open

position, and stop means engageable with said release lever for limiting rotation thereof about said first axis and movement of the release valve actuator at an index position, said release lever being rotatable about a second axis angularly related to said first axis and intersecting the point of engagement with said stop means to effect additional movement of the release valve actuator beyond said index position.

2. A release mechanism for controlling the rate of lowering of a hydraulic jack wherein the rate of lowering is related to movement of a release valve actuator towards the open position, said release mechanism comprising a release lever of generally U-shaped configuration defined by a bight portion having depending leg portions the ends of which are supported for rotation, respectively, about a common axis whereby said lever is rotatable in a plane generally normal to the bight portion thereof to engage and move the release valve actuator of the jack towards the open position, an adjustable stop screw secured to the bight portion of said release lever relatively closer to one of the leg portions thereof than to the other leg portion, and a stop bracket engageable with said stop screw for limiting movement of said lever thereby to limit movement of the release valve actuator to an index position, said release lever being bendable about an axis extending between the point of engagement of said stop screw with said stop bracket and the pivotal support for the other of the leg portions of said release lever to effect movement of the release valve actuator towards the open position and beyond said index position.
